[57] CLAIM

The ornamental design for a wheel, substantially as
shown and described.

DESCRIPTION

FIG. 1 is a perspective view taken from the front and
left side of a wheel embodying of my new design.

FIG. 2 is a front elevational view thereof.

FIG. 3 is an end elevational view thereof.

FIG. 4 is a rear elevational view thereof.

FIG. 5 is a cross-sectional view thereof taken along line
5—5 of FIG. 2.

The pattern as shown in FIGS. 1 and 2 is understood to
be repeated uniformly throughout the full circumfer-
ence of the wheel.
